PEG BOARD BRACKET

Leerie O. Baker, College St., Greenville, Ill. 62246

Filed June 21, 1967, Ser. No. 7,540

Term of patent 14 years

(Cl. D54—1)

FIG. 1

FIG. 2

FIG. 3

FIG. 4

FIG. 1 is a top perspective view of a peg board bracket showing my new design;

FIG. 2 is a bottom perspective view of the peg board bracket, showing the surfaces and sides not seen in FIG. 1;

FIG. 3 is a top perspective view of a modified form of the peg board bracket shown in FIG. 1; and

FIG. 4 is a top perspective view of another modified form of the peg board bracket shown in FIG. 1.

I claim:

The ornamental design for a peg board bracket, as shown and described.
